(57) **CLAIM**

The ornamental design for an insect killer machine, as shown and described.

DESCRIPTION

FIG. 1 is a perspective view of an insect killer machine showing my new design;

FIG. 2 is a front view thereof, a rear view being identical to the front view;

FIG. 3 is a right side view thereof, a left side view being identical to the right side view;

FIG. 4 is a top view thereof; and,

FIG. 5 is a bottom view thereof.

The broken line showing of an inner portion of the design is included for the purpose of illustrating only and forms no part of the claimed design.
